ABSTRACT OF THE DISCLOSURE

Threaded handles are applied on semi-automatic machinery to threaded stoppers in a filled hypodermic syringe to form a plunger. The machine has a series of cylinders of suitable size to receive the barrels of the syringes. These cylinders are provided at the top with soft gaskets of elastomer to grip the syringe barrel. Handles for the syringes, provided with ribs to prevent turning, are then dropped into syringe barrels inserted in the cylinders of the machine. Guide plates with suitable holes guide the handles as they are inserted. Movable locking plates adjacent to the cylinder handles are swung into position and prevent turning of the handles when the cylinders turn. The threaded handles are inserted, and then a second bar having rods aligned to contact the top of the handles is lowered. The rods are provided with light springs so that when lowered they press against the handles with a light, predetermined pressure. The cylinders are then rotated in the proper direction to screw the threaded handles into the threaded stoppers. The light spring pressure assures that there is sufficient pressure to screw in the handles but insufficient pressure to cause the stopper to move and thus discharge part of the contents of the syringe. The soft elastomer gaskets around the tops of the cylinders grip the syringe barrels sufficiently so that the barrels are turned when the cylinders turn.

BACKGROUND OF THE INVENTION

Disposable hypodermic syringes are extensively used today. These syringes are filled with a predetermined volume of liquid and then an elastic stopper with female threads is dropped down onto the surface of the liquid. Finally, handles having cooperating male threads are inserted into the syringe barrels and then are screwed into the female threads of the stopper, thus forming a unitary plunger.

Problems are presented by the fact that when the handles are inserted and screwed in by hand, as was the practice hitherto, the operation is slow and production outputs are limited. An even more important problem is presented by the fact that there is a relatively narrow range of pressure which can be applied to the handles while they are being screwed in. A certain minimum is needed to assure that the threads catch, but if there is too much pressure, the rubber stopper can be moved down, which causes some of the liquid in the syringe to be expelled, thus changing the dosage and creating other problems. As a result, a number of rejects are produced, particularly near the end of the day when the operator is tired, and this of course is economically highly undesirable.

SUMMARY OF THE INVENTION

The present invention provides an automatic machine which screws in handles in a large number of syringes simultaneously and provides an accurate, predetermined, gentle pressure which is sufficient to cause the threads to catch but insufficient to move the stoppers. As a result,

2

output is speeded up and rejects are substantially eliminated.

The machine is provided with a number of cylinders of suitable size to take the barrels of syringes with the needle down. The tops of the cylinders have a gasket of elastic material, such as rubber, so that when the cylinders are turned the barrels turn with them but the friction is light so that when the handles are fully screwed into the stoppers the cylinders can slip for a short distance. In other words, the light friction of the rubber gaskets operate as a weak clutch, holding only sufficiently so that the syringe barrels are turned while the handles screw into the stoppers.

A second bar is then lowered with rods aligned to strike the handles, and each rod is provided with a predetermined light spring which exerts a definite and accurate light pressure on the top of the handles. The cylinders are then started to rotate, turning the barrels in the proper direction to screw the threaded handles into the stoppers. When the handles have been seated, the cylinders stop turning, the bars are raised, the syringes removed, and the operation repeated.

In order to speed up operations, the syringe barrels are mounted in holes in a carrier tray so that a number can be introduced into the cylinders at the same time.

As it takes no longer to screw in handles in a large number of syringes simultaneously than it does to screw one in by hand, great increase in production output is made possible. At the same time, the spring pressure is accurately predetermined so that it is just right to hold the handles sufficiently so that the threads will catch but is not great enough to move the stoppers in the barrels. After introduction of the handles the bar carrying the rods can be lowered manually or the actuation can be effected mechanically, for example pneumatic actuation. The exact method by which the bars are moved does not, strictly speaking, form any part of the present invention, but because of the simplicity of actuation, pneumatic means are preferred and will be described in the more specific description below; but of course the invention is not limited in its broader aspects to pneumatic actuation of the bars or to any other particular method of bringing them into position.

The cylinders and the carrier trays can readily be changed to accommodate different sizes of syringes. This adds a desirable flexibility and versatility to the machine and constitutes a practical operating advantage. Obviously of course, if the machine is to be used for only one syringe size, the cylinders may be mounted more permanently. However, as it is quite simple to change cylinders and locking bars, it is normally desirable to use this modification even though changes in syringe size may not be immediately contemplated.

BRIEF DESCRIPTION OF THE DRAWINGS

FIGURE 1 is a section through a disposable syringe with the handle separated from the stopper;

FIGURE 2 is a front elevation, partly broken away, of a machine before introducing syringes;

FIGURE 3 is a similar elevation, but not broken away, of the same machine with syringe barrels introduced into the cylinders, locking plates applied, and some of the handles introduced;

FIGURE 4 is a similar front elevation with the bar containing spring pressed rods lowered into contact with the handles;

FIGURE 5 is a side elevation, partly in section, showing pneumatic actuation of the bar carrying rods; and

FIGURE 6 is a detail plan view of a handle and the two locking plates for preventing turning.

DESCRIPTION OF THE PREFERRED EMBODIMENTS

FIGURE 1 shows a typical syringe and as such may represent the prior art. The syringe has a barrel 1 partly filled with the liquid 2 and, of course, the conventional needle 3. On top of the liquid in the barrel there is placed a stopper 4, for example of rubber, provided with internal female threads 5. The barrel has the customary finger grips 6 and a handle 24 with ribs 7 is shown inserted but not quite touching the stopper 4. This handle is provided with male threads 8. In the figure the ribs are shown with one pair in the plane of the paper for clarity, actually FIGURE 1 represents a handle which is positioned about 45° from the actual position in the machine as can be seen from FIGURE 6. From the latter figure it is apparent that the ribs must be oriented so that they extend at an angle somewhere in the neighborhood of 45° to the locking plates 17 which engage the ribs and prevent any substantial turning of the handle after the ribs strike the locking plate 17.

Turning to FIGURES 2 and 5 it will be seen that the machine is provided with a top plate 9, a front plate 10, and a series of cylinders 11 which pass through openings in the top plate and are fastened to shafts 12 turned through the bevel gears 13 by the motor 14. The cylinders are detachably mounted on their shafts and carry at their tops a ring of elastic material 15. For economy of space, shafts 12 of each pair of cylinders are turned from a single spur gear 25 meshing with two small spur gears 26 on the end of each shaft. The gears 25 are in turn mounted on short stub shafts 27 each of which is driven by a bevel gear 13.

FIGURE 3 shows the same machine as in FIGURE 2 with a series of syringe barrels 1 inserted in the cylinders. The barrels are held in openings in a plate 16 which forms part of a tray provided with an additional upper plate 28 having guide holes 19 through which handles are inserted into the barrels as will be described below. The whole tray is hung onto the framework with a short channel section 29. This can best be seen in FIGURE 3 which shows only two openings 19 in order not to confuse the drawings, one handle is shown moving through an opening 19 and a second handle just before introducing into another hole 19. This second handle, as in FIGURE 1, is shown with the rib 7 in the same position as in FIGURE 1 for clarity. Of course before the handle is inserted it is slightly turned so that the ribs 7 can pass between locking plates as will be described below. Exact orientation is not necessary which permits rapid operation because even if the ribs are not perfectly in position when cylinders start to turn the barrel the handles will turn slightly until a rib encounters a locking plate which will be described.

FIGURE 2 shows a pair of locking plates 17 fastened to shafts 30 which are turned by knurled knobs 31. In their raised position the locking plates permit removing a tray of syringes with handles inserted and also inserting a fresh tray containing the barrels as has been described above. The knurled knobs are then turned bringing the two locking plates 17 close to the ribs 7, as is best seen in FIGURE 5 although FIGURES 3 and 4 also show one locking plate 17 in the closed position. FIGURES 6, of course, also shows the plates in the closed or locking position and this figure shows why the plates lock the ribbed handles and keep them from turning.

FIGURE 4 shows a bar 20 lowered by the pneumatic cylinder 23. FIGURE 5 illustrates the operation of the pneumatic cylinder which moves links 32, pivoted in the framework, and which cause the bar 20 to be raised or lowered. In FIGURE 5 the lowered position is shown in full lines and the raised position in dashed lines. The bar 20 is provided with a series of rods 21

which are urged against the tops of the handles by light, predetermined spring pressure. The bar is shown broken away at one end to illustrate a spring 22. The structure is also shown in section in FIGURE 5 and it will be apparent that the rods can move only a certain distance before their flanges 33 strike shoulders 34. In FIGURE 4 the rods 21 are shown almost striking the shoulders 34.

After both bars are in place, as is shown in FIGURE 4, the motor is started and all of the cylinders turn in the proper direction, screwing the threaded handles into the rubber stoppers. As the pressure by the spring 22 is accurately predetermined and is too slight to move the stoppers, no liquid escapes. However, the pressure is sufficient to urge the threaded ends of the handles into the recesses in the stoppers so that the handles are reliably screwed into each stopper. As the cylinders start turning and the handles screw into the stopper the first small motion brings the rods 21 down until the collars 33 strike the shoulders 34. Thereafter as a handle screws in there is no spring pressure on it. Of course, by the time the handle has been screwed in all the way there will be a slight gap between the end of each rod 21 and the top of its corresponding syringe handle. However, as FIGURE 4 shows the position just before the cylinders start turning, no gap appears on this figure.

As has been mentioned above, when the handles are screwed in all the way the friction of the barrels 1 against the stoppers 4 is much greater than between the elastic collar of each cylinder and the syringe barrel permitting a little slip, because at this point there is no spring pressure and the barrels are held against the elastic gaskets 15 only by their small weight. The very slight slippage when the handle is entirely screwed in, which may be a very small fraction of a turn, is provided to assure that all handles are screwed in completely.

After the handles are all screwed in, the motor is shut off, the pneumatic cylinder is actuated, which raises bar 20, the knobs 31 are then turned to raise the locking plates 17 to the position shown in FIGURE 2 which permits removing the set of syringes. A new set is then introduced into the cylinders, the operations then being repeated.

If it is desired to operate with a different size of syringe, the cylinders are detached and replaced with other cylinders of the proper size. The operation of the machine is, of course, the same as has been described above.

What is claimed is:

1. An apparatus for automatically screwing in handles in disposable hypodermic syringes which have been filled with a dose of liquid and provided with resilient stoppers having a threaded central recess engaging a threaded end on the handles, comprising in combination,
- (a) a housing having an upper plate,
- (b) a series of cylinders on said plate and having projections therethrough, the cylinders having an internal diameter corresponding to the external diameter of syringe barrels, and a resilient ring at the top of each cylinder capable of gripping a syringe barrel,
- (c) means for rotating the cylinders in a direction to screw syringe barrels containing a stopper onto threaded handles,
- (d) a movable locking bar fitting over the syringes in the cylinders, said bar having openings of size sufficient to permit introducing threaded handles therethrough and being aligned over the cylinders, whereby when the locking bar is in contact with syringe barrels in the cylinders, threaded handles can be introduced through the openings in accurate alignment with the barrels,
- (e) a vertically movable bar provided with movable rods engageable with handles in each syringe when,

the bar is lowered, the rods being under predetermined, light, resilient pressure sufficient to hold a handle in contact with a stopper but insufficient to move a stopper in the syringe barrel, whereby when the cylinders are rotated the barrels of each syringe are rotated therewith and the stoppers screwed onto the threaded ends of the handles.

2. An apparatus according to claim 1 provided with pneumatic actuating means for moving the two bars.
3. An apparatus according to claim 2 in which the

resilient pressure of the rods is provided by individual springs.
